United States Patent Office

Des. 234,172
Patented Jan. 28, 1975

234,172

DISPLAY STAND

Daniel R. Ranney, 36 Phillips St.,
Boston, Mass. 02148

Filed June 11, 1973, Ser. No. 368,515

Term of patent 14 years

Int. Cl. D20—02

U.S. Cl. D6—85

FIG. 3

FIG. 4

FIG. 1 is a perspective view of a display stand showing my new design;

FIG. 2 is a side elevation thereof;

FIG. 3 is a front elevation thereof; and

FIG. 4 is a top view thereof.

I claim:

The ornamental design for a display stand, as shown and described.
